LOOP AND BUTTON CLASP.

1,236,120.

Specification of Letters Patent.

Patented Aug. 7, 1917.

Application filed August 18, 1914. Serial No. 857,354.

To all whom it may concern:

Be it known that I, HENRY J. STUART, a citizen of the United States, residing at Derby, in the county of New Haven and State of Connecticut, have invented a certain new and useful Improvement in Loop and Button Clasps, of which the following is a specification.

My invention relates to button clasps for garment supporters and like articles, but more particularly to that class of the same in which the button is provided with an elastic collet.

The object of my invention is to provide a button having an elastic collet and a tape-covered base plate which can be economically and quickly assembled.

I attain this and other objects of my invention in the device set forth in the following description and accompanying drawings in which like reference characters refer to corresponding parts.

In the drawings:

Figure 1 is a front view of the lower extremity of a hose supporter;

Fig. 2, a central longitudinal sectional view thereof;

Fig. 3, detail views of the rubber collet forming the head and shank of the button;

Fig. 4, a top plan view of the button base and stud;

Fig. 5, a front view of a fragmentary portion of the apertured tab;

Fig. 6, a side view of the base and stud showing the tab secured to the stud, and

Fig. 7, a side view of the button after its parts have been assembled.

The button clasp, which is shown depending from a fold in the extremity of the supporting strap A, consists of an attaching link B, a button loop C, and a button take or tab D which carries a button E at its lower extremity. The button loop C, which is connected to the lower side of the link B by a lip F projecting from the upper side thereof, is provided with a bridge G and has the sides of its lower extremity contracted to engage the shank of the button E. With the exception of the button E the device thus far described is one of the common forms of loop and button clasps well known in the art. Referring to Figs. 1 to 7 inclusive, in which the parts are shown enlarged the button E consists of a metal base

2 which is narrower in width than the tab 55 D. Projecting outwardly and riveted to the base 2 is a wire stud 3. The stud 3 is headed to form a convex cap 4, which is preferably annularly recessed on its under side, to form a peripheral biting edge 5. 60 The elastic rubber collet 6 is shaped to form a head 7 and a shank 8. The collet 6 is provided with a central aperture 9 having an inside cylindrical wall 10 flared outwardly at its upper extremity. The diameter of 65 the wall 10 is less than that of the head 4 and preferably less than that of the stud 3. One extremity of the tab D is punched, before it is applied to the button, to form an aperture 11.

To assemble the button, the stud 3 is first riveted to the base 2. Then the apertured extremity of the tab D is slipped over the head 4 of the stud, or to be more exact the head 4 is slipped through the aperture 11 70 in the extremity of the tab, thereby securing the tab to the stud so that its upper end 12 will slightly overlap one end of the base 2, as shown in Fig. 6. The rubber collet is then sprung over the stud by first placing 75 the under side of its shank 13 against the head 4 then pressing down causing the head to distort the rubber in the wall 10 of the aperture as the collet passes down on the stud. The pressure of the collet is continued 80 until the under side of its shank 13 presses the edges of the aperture 11 in the tab hard against the front face of the base 2. The vertical dimension of the collet and stud are preferably so arranged relatively to each 85 other that, when the downward pressure on the collet is relieved, the latter springs upwardly engaging the underside of the head 4, and causes the peripheral edge 5 of the latter to become embedded in or bite into the 90 flaring extremity of the wall 10 of the aperture. In this manner the collet is held between the under side of the head of the stud and the top of the base, or to be more exact the front of the tape-covered base, and co-acts with the base to prevent displacement 95 of the tab. The tab is then carried around in back of the base 2 and upwardly through the link B, then downwardly and rearwardly through the loop passing over the top of the bridge G. The overlapping ends 12 and 14 of the tab are then sewed together by 100 stitches 15 immediately adjacent to the

upper end of the base 2, the end 12 being folded in to form a hem which prevents fraying. The button base, being confined between the layers of the tab which are 5 wider than the base, is entirely covered and concealed, thereby obviating any disadvantages incident to the exposure of a metal part. It should be noticed that the expansive force exerted by the rubber forming 10 the collet effects a grip between the parts which prevents them from becoming loose from wear and strain and also prevents them from being twisted out of longitudinal alinement. For this reason it is not necessary 15 to close the layers of the tape along the side edges of the base. In the above description I have referred to the collet as being made of spring or elastic rubber, yet I may employ a collet made out of any other material 20 having characteristics which will enable it to be sprung on to a headed stud. I prefer, however, to employ a collet made of spring rubber since it is the best material, so far as I am aware, to hold the parts together and to grip the garment.

While the preferred forms of my invention are embodied in the devices above described yet the same are susceptible to such modifications as may fairly come within the 25 scope of the appended claims.

Having now described my invention what

I desire to claim and protect by Letters Patent is:

1. In a button clasp a button comprising a base on which is mounted a headed stud, the said base having its front side covered with tape which surrounds the stud and a spring rubber collet surrounding said stud in front of the tape and containing a passage therethrough of less diameter than the head of the stud, the said collet being held against the tape by the under side of the head of the stud, and the said stud passing entirely through said collet.

2. In a button clasp a button having a 45 base on which is mounted a headed stud, the said base having its front side covered with fabric material through which said stud extends and an elastic collet slipped over the stud in front of the fabric material and containing a passage therethrough of less diameter than the head of the stud, the said stud passing entirely through the collet which latter entirely fills the space between the front side of the fabric material and the 50 under side of the head of the stud.

In witness whereof I have hereunto set my hand on this 23rd day of July, 1914.

HENRY J. STUART.
